(57) **CLAIM**

The ornamental design for a screwless wall plate assembly, as shown and described.

DESCRIPTION

Cross-reference to related applications: U.S. patent application Ser. No. 29/213,936.

FIG. 1 is a perspective view of a screwless wall plate assembly showing our new design;

FIG. 2 is a front elevational view thereof;

FIG. 3 is a top plan view thereof;

FIG. 4 is a bottom plan view thereof;

FIG. 5 is a left side elevational view thereof, the right side being a mirror image;

FIG. 6 is a back elevational view thereof;

FIG. 7 is a perspective view of a second embodiment of a screwless wall plate assembly showing our new design;

FIG. 8 is a front elevational view thereof;

FIG. 9 is a top plan view thereof;

FIG. 10 is a bottom plan view thereof;

FIG. 11 is a left side elevational view thereof, the right side being a mirror image;

FIG. 12 is a back elevational view thereof;

FIG. 13 is a perspective view of a third embodiment of a screwless wall plate assembly showing our new design;

FIG. 14 is a front view elevational view thereof;

FIG. 15 is a top plan view thereof;

FIG. 16 is a bottom plan view thereof;

FIG. 17 is a left side elevational view thereof, the right side being a mirror image; and,

FIG. 18 is a back elevational view thereof.
